2 SHEETS—SHEET 2.

UNITED STATES PATENT OFFICE.

HERMAN FAJANS AND ALEXANDER M. CHAMBERS, OF NEW YORK, N. Y.

CAR-FENDER.

No. 926,398.

Specification of Letters Patent.

Patented June 29, 1909.

Application filed February 8, 1909. Serial No. 476,648.

To all whom it may concern:

Be it known that we, HERMAN FAJANS and ALEXANDER M. CHAMBERS, citizens of the United States, and residents of the city of 5 New York, borough of Brooklyn, in the county of Kings and State of New York, have invented a new and Improved Car-Fender, of which the following is a full, clear, and exact description.

10 The invention is an improvement in fenders for power-driven cars and in general consists of a fender frame, an upright frame, arms adjustably and pivotally supported at their inner ends from the car and at their 15 outer ends pivotally supporting the fender frame intermediate its length and having a sliding connection therewith, a slide carried by the upright frame yieldingly pressed to the upper portion thereof, a net connected to 20 the forward portion of the fender frame and to the slide, means to lock the inner end of the fender frame to hold the outer end thereof above the ground, automatically disengaged and permitting the fender frame to 25 swing to the ground at its outer end and upwardly at its inner end on the arms when the fender strikes an object which is received in the net, and means to automatically lock the inner portion of the fender frame in its 30 upper position.

Reference is to be had to the accompanying drawings forming a part of this specification, in which similar characters of reference indicate corresponding parts in all the views.

35 Figure 1 is a side elevation, partly in longitudinal vertical section, of a fender embodying our invention as applied to a car, the fender being shown in full lines in operative position, in dotted outline after striking an 40 object and in dotted outline when moved to an inoperative position; Fig. 2 is a front elevation of the fender when in operative position; and Fig. 3 is a perspective view of one of the blocks or hangers which carry the 45 inner portions of the fender frame and supporting arms.

In carrying out our invention we provide two blocks or hangers 5, 5, which are arranged at and secured to the front of the car 50 platform, for which purpose each block has an offset foot 5^a. Each block is vertically slotted, with the lower portion of the slot separated from the upper portion by a cross-key 6, adjacent to which the front wall of the 55 slot has a recess or seat 7, and at a substan-

tial distance above this recess the rear wall of the slot has a similar recess or seat 8. At the side of each block, opposite the recess or seat 7, is a pivotally suspended cylinder 9 having a spring-pressed piston, as best shown 60 in dotted outline in Fig. 1, the stem of which at the outside of the cylinder is provided with a clamping or locking head 10. The cylinder is normally retained in a horizontal position by a finger 11, a stop-pin 12, and a 65 spring 13 forcing the finger to the stop-pin.

Each block 5, opposite the recess or seat 8, is provided with a bell-crank locking lever or dog 14 normally pressed to locking position by a spring 15, the latter surrounding an 70 operating stem 16 of arcuate form, which passes through an opening in the front of the block. When the dog 14 is in locking position its foot rests against the inner wall of the 75 block and its inner end projects into the vertical slot of the block.

A vertical frame 17 of tubular construction and inverted U-form has its lower ends securely anchored in the blocks and passed through top plates 18 covering the slots in 80 the blocks and having interfitting outer end portions. These plates when raised above the top faces of the blocks may be swung on the frame 17 from over the vertical slots which they cover. On each of the upright 85 arms of the frame 17 is arranged a spring 19. These springs press on the under side of sleeves 20 rigidly connected together by a cross-bar 21 and constituting a sliding frame. Each spring 19 is inclosed by telescoping tubular casings 22, one section of which is carried by the sleeve 20 and the other section seating on the top plates 18. 90

The inner end portion of the rectangular tubular fender frame 23 passes through the 95 vertical slots of the blocks 5 between the cross-keys 6, and is adjustably and pivotally supported intermediate its length by arms 24, which are connected together at their inner ends by a cross portion also passing through the vertical slots of the blocks below the cross-keys 6. This cross portion of the arms adjacent to each block is provided with a wheel 25 having oppositely-arranged teeth, the two sets of teeth being engaged by pawls 26 pivotally supported on the block 5 and operating to lock the arms against pivotal movement in either direction. The connection between the arms and the fender frame 100 is effected by providing the outer end of each 105 110

arm with a pivotally connected sleeve 27
slidable on the side-bars of the frame. In
the outer portion of the fender frame is jour-
naled a crank-shaft 28, the outer ends or
5 crank-arms of which are turned inwardly and
carry supporting wheels 29. A net 30 is con-
nected to the crank-shaft 28 at its forward
end, and at its inner end is connected to the
10 cross bar 21 of the sliding frame, the cross
bar normally retaining the net fully stretched.
The net is preferably of link or chain con-
struction and at its forward end is connected
to the side-bars of the fender frame by a se-
ries of links 30^a.

15 The fender in operative position is as
shown in full lines in Fig. 1, in which case the
inner cross-bar of the fender frame 23 is seat-
ed in the recesses or seats 7 of the blocks 5
and is yieldingly retained therein by the
20 spring-pressed heads 10; these, in connection
with the supporting arms 24, holding the for-
ward portion of the fender above the ground,
the elevation of which may be regulated by
the pivotal adjustment of the arms. When
25 the fender strikes an object the inner cross-
bar of the fender frame is disengaged from
the spring-pressed heads 10 and moves up-
wardly in the vertical slots of the blocks into
the recesses 8 thereof, where it is automati-
30 cally locked by the dogs 14 while the for-
ward portion of the fender frame moves to
the ground. The object struck falls upon
the net 30, the latter sagging down in the
fender frame under the weight of the object
35 to form a basket, as shown in dotted outline
in Fig. 1, this sagging of the net being of
course due to the pulling down of the vertical
sliding frame against the tension of the
springs 19. When the object is removed
40 from the net the forward portion of the fender
frame may be easily raised after drawing
the operating stems 16 of the dogs 14 out-
wardly. The inner cross-bar of the fender
frame as it passes down in the vertical slots
45 of the blocks 5 strikes the spring-pressed
heads 10, tilting the cylinders 9 on their piv-
ots until the cross-bar passes within the re-
cesses 7 of the blocks, at which time the
springs 13 return the cylinders to a hori-
50 zontal position and the spring-heads into enga-
gement with the fender frame. When the
fender is not in use it may be thrown to a
vertical position, as shown in dotted outline
in Fig. 1, and be thus secured by the pawls 26.

55 Having thus described our invention, we
claim as new and desire to secure by Letters
Patent:

1. In a car fender, a fender frame, pivoted
60 arms pivotally supporting the frame inter-
mediate its length from the car adjustable
on their pivots to different elevations, and
means to lock the frame against pivotal move-
ment, with the outer end portion there-
65 of above the ground, automatically disen-
gaged when the fender strikes an object, per-

mitting the outer portion of the frame to
move to the ground and the inner portion to
move upwardly.

2. In a car fender, a fender frame, means
pivotally supporting the frame intermediate 70
its length from the car, means to lock the
frame against pivotal movement, with the
outer end portion thereof above the ground,
automatically disengaged when the fender
strikes an object, permitting the outer por- 75
tion of the frame to move to the ground and
the inner portion to move upwardly, and
means to automatically lock the inner por-
tion of the frame in its upper position.

3. In a car fender, a fender frame, pivoted 80
arms pivotally supporting the frame inter-
mediate its length from the car, means to
lock the inner end portion of the frame, with
the outer end portion thereof above the ground,
automatically disengaged when the 85
fender strikes an object, and means to hold
the arms in different positions of adjustment
on their pivots.

4. In a car fender, a fender frame pivotally
supported at its inner end portion on the car, 90
arms rigidly connected at their inner ends
and pivotally supported on the car, each
arm having a pivotally-connected member
at its outer end slidable on the fender frame,
means to lock the arms in adjusted position, 95
and means to secure the inner end portion
of the fender frame, automatically disen-
gaged when the fender strikes an object, per-
mitting the fender frame to swing on the
arms.

5. In a car fender, a fender frame pivotally
supported at an intermediate point of its
length from the car, means to secure the
inner end portion of the frame, with the
outer end portion thereof above the ground, 105
automatically disengaged when the fender
strikes an object, a vertical frame supported
on the car, a sliding frame on the vertical
frame, means normally forcing the sliding
frame to an upper position on the vertical 110
frame, a crank-shaft journaled in the outer
portion of the fender frame having support-
ing wheels, and a net connected to the crank-
shaft and to the sliding frame.

6. In a car fender, outwardly-extending 115
arms pivotally supported at their inner ends
on the car, means to lock the arms in adjust-
ed position, a fender frame having a sliding
pivotal connection with the arms, means enga-
ging the inner end portion of the frame to
secure the frame against pivotal movement,
automatically disengaged when the fender
strikes an object, and a yielding net to re-
ceive and retain the object, having its outer
end connected to the fender frame and its 120
inner end supported a substantial distance
above the inner portion of the fender frame.

7. In a car fender, vertically slotted sup-
porting blocks having recesses in the oppo-
site walls of the slots, a fender frame, means 130

- carried by the blocks pivotally supporting the fender frame intermediate its length, and means to lock the inner portion of the fender frame in the lower recesses of the blocks, automatically disengaged when the fender strikes an object, permitting the outer end portion of the fender frame to swing to the ground and the inner end portion to swing into the other recesses of the blocks.
8. In a car fender, vertically-slotted supporting blocks, outwardly-extending arms journaled on the blocks at their inner ends, means to lock the arms in adjusted position, a fender frame pivotally supported on the outer ends of the arms, with the inner end portion of the frame passing through the slots of the blocks, means to secure the inner portion of the fender frame in the lower portions of the slots of the blocks, automatically disengaged when the fender strikes an object, whereby the outer end portion of the frame swings to the ground and the inner end portion thereof moves upwardly in said slots, and spring-pressed dogs carried by the blocks to automatically lock the inner end portion of the frame in its upper position in the slots of the blocks.
9. In a car fender, vertically-slotted supporting blocks, a fender frame pivotally supported intermediate its length from the blocks, with the inner end portion of the frame passing through the slots of the blocks, a pivoted cylinder having a spring-pressed member to lock the inner end portion of the frame in the lower portions of the slots, means yieldingly forcing the cylinder to an operative position, and a spring-pressed dog to automatically lock the inner end portion of the fender frame in the upper portions of the slots when the frame is released by the spring-pressed means of the cylinder.
10. In a car fender, a fender frame supported from the car, an approximately vertical frame supported on the car above the inner end portion of the fender frame, a sliding frame on the vertical frame, springs arranged on the vertical frame normally forcing the sliding frame to an elevated position, a net connected to the forward portion of the fender frame and to the sliding frame, and telescoping casings surrounding the springs.
11. In a car fender, supporting blocks, outwardly-extending arms journaled on the blocks, means to lock the arms in adjusted position, a fender frame slidably and pivotally connected with the outer ends of the arms, a swinging cylinder having a spring-pressed plunger to lock the inner end portion of the fender frame to the blocks, automatically disengaged when the fender strikes an object, and means to automatically lock the inner end portion of the fender frame in an elevated position when released by the spring-pressed means of the cylinder.
